(57) **CLAIM**

The ornamental design for a foldable desk frame as shown and described.

DESCRIPTION

FIG. 1 is a front, left side perspective view of a foldable desk frame showing my new design.

FIG. 2 is a front perspective view thereof.

FIG. 3 is a rear perspective view thereof.

FIG. 4 is a left perspective view thereof.

FIG. 5 is a right perspective view thereof.

FIG. 6 is a top view thereof.

FIG. 7 is a bottom perspective view thereof; and,

FIG. 8 is a rear, left side perspective view thereof.

The broken lines in the drawings depict portions, including the tabletop, the mounts for the tabletop and the hinge screws, of the Foldable Desk Frame form no part of the claimed design.

1 Claim, 8 Drawing Sheets
